UNITED STATES PATENT OFFICE.

HENRY I. ROGERS, OF FORT FAIRFIELD, MAINE.

ASH-PAN AND APRON FOR FURNACES.

1,158,296.

Specification of Letters Patent. Patented Oct. 26, 1915.

Application filed July 20, 1915. Serial No. 40,959.

To all whom it may concern:

Be it known that I, HENRY I. ROGERS, a citizen of the United States, residing at Fort Fairfield, in the county of Aroostook and State of Maine, have invented certain new and useful Improvements in Ash-Pans and Aprons for Furnaces, of which the following is a specification.

This invention has relation to furnaces and more particularly to the base or pit, the purpose being to insure the delivery of the ashes, cinders and the like into an ash-pan, thereby avoiding the necessity of having to shovel the ashes from the pit which operation is prolific of scattering dust besides requiring the stooping or bending of the operator when manipulating the shovel and which operation is objectionable and inconvenient.

In accordance with the present invention the base or ash pit of a furnace is provided with an ash pan the back of which is designed to snugly fit the back of the ash pit to insure delivery of the ashes into the pan.

The invention also consists of aprons or deflectors located along the sides of the base or ash-pit and disposed to overhang the sides of the ash-pan thereby directing the ashes from the grate into the pan and preventing the ashes from accumulating in the spaces between the sides of the pan and the side walls of the base or pit.

The invention, furthermore, consists of mountings of novel form for attaching the aprons or deflectors to the base, said mountings admitting of the aprons being easily placed in position and quickly removed as occasion may require.

With these and other objects in view, which will readily appear as the nature of the invention is better understood, the same consists in the improved construction and novel arrangement and combination of parts which will be hereinafter fully described and particularly claimed.

In the accompanying drawings has been illustrated a simple and preferred form of the invention, it being, however, understood that no limitation is necessarily made to the precise structural details therein exhibited, but that changes, alterations and modifications within the scope of the invention as claimed may be resorted to when desired.

Referring to the drawings,—Figure 1 is a perspective view of a furnace having its base or ash-pit provided with an ash-pan

and aprons embodying the invention, a portion of the furnace and base being broken away to show more clearly the relation of the parts. Fig. 2 is a perspective view of the ash-pan, one of the aprons or deflectors, together with the mountings therefor and a portion of the grate and grate-rest. Fig. 3 is an enlarged transverse section of the base or ash-pit. Fig. 4 is a detail perspective view of one of the mountings for the apron or deflector.

Corresponding and like parts are referred to in the following description and indicated in all the views of the drawings by the same reference characters.

The numeral 1 designates a furnace of any make or type provided with a base or ash-pit 2, the same being provided with a grate 3 of any type and a grate-rest 4, the latter being secured to the base or ash-pit 2 in any well known manner. As indicated in Fig. 1 the back of the base or ash-pit is made rounding, such form being usual. An apron or deflector 5 extends along each side of the base or ash-pit with its lower portion inclining inwardly and downwardly so as to direct the ashes away from the side walls of the ash-pit and into the ash-pan 6. The upper portion of the base or ash-pit 2 is formed with an inwardly extending ledge 7 which extends over the upper portions of the aprons or deflectors 5 and part way over the grate rest 4, thereby causing the ashes to drop upon the aprons which latter deflect the ashes inward and cause them to fall into the pan 6. The inwardly extending ledge 7 may be provided in any well known way. The aprons or deflectors 5 consist of sheet metal plates which may be of any length and width. The inner or rear ends of the aprons 5 are curved to conform to the rear wall of the ash-pit or base 2 so as to obtain a close fit therewith. The front ends of the aprons terminate about in the plane of the front wall of the ash-pit or base. The upper longitudinal portion of each apron or deflector 5 comprises a vertical portion 8 and a horizontal portion 9, the same being formed by bending the upper edge portion 105 of the plate. The vertical portion 8 of the apron extends along the outer edge of the longitudinal portion of the grate rest 4 and the horizontal portion 9 is disposed beneath the ledge 7 and comes close against the inner 110 wall of the ash-pit or base.

Each of the aprons is retained in place

by suitable mountings usually two being employed in connection with each apron.

These mountings are preferably formed of sheet metal of proper gage and each of 5 the mountings comprises a horizontal portion 10, an inclined portion 11, a vertical portion 12 and oppositely extending wings 13 and 14. The wings 13 and 14 are formed by a slit extending inward from an end of 10 the blank from which the mounting is formed and bending the portions in opposite directions separated by the slit. The inclined portion 11 is riveted or otherwise secured to the inclined portion of the apron or deflector. 15 The vertical portion 12 extends along the outer side of the vertical portion 8 of the apron whereas the wing 14 extends under the horizontal portion 9 of the apron and in conjunction with the part 10 serves to space 20 the apron from the side wall of the pit or base. The wing 13 extends over the grate-rest 4, thereby retaining the apron in position and admitting of the same being easily removed when required.

25 The ash-pan 6 is of a length corresponding to the length of the ash-pit and its rear wall 15 is inclined and made rounding so as to conform to the rear curved wall of the ash-pit or base. A handle 16 is pivotally 30 connected to the rear inclined wall 15 of the ash-pan and serves in conjunction with the handle 17 attached to the front of the ash-pan as convenient means for carrying the pan when laden with ashes. The ash-pan 35 is of a width less than the distance between the longitudinal side walls of the ash-pit or base so as to slide freely through the usual door leading into the front of the ash-pit. When the ash-pan is slid into position into 40 the ash-pit it occupies a central position and comes beneath the inner lower edge portions of the aprons or deflectors 5 which overhang side portions of the ash-pan a distance to insure the delivery of the ashes into the 45 pan and thereby prevent the discharge of the ashes into the spaces formed between the sides of the ash-pan and the side walls of the ash-pit.

It will be understood from the foregoing 50 taken in connection with the accompanying drawings that the invention provides means whereby the ashes of a furnace are dis-

charged into a pan, thereby enabling such ashes to be removed from the ash-pit or base without causing dust or the inconvenience 55 and annoyance incident to shoveling the ashes from the pit into a scuttle or other receptacle.

Having thus described the invention, what is claimed as new is:—

1. An ash-pit provided with a grate rest, longitudinally disposed aprons at the sides of the ash-pit inclining inwardly and downwardly toward their lower edges, and mountings secured to the aprons and having portions extending over the grate rest and other portions projecting outwardly to engage the side walls of the pit and space the aprons therefrom.

2. In an ash-pit, oppositely disposed longitudinal aprons inclining inwardly and downwardly toward their lower edges, and mountings attached to the upper portions of the aprons and having upper and lower outwardly directed portions engaging the side 75 walls of the pit to properly support and space the said aprons therefrom.

3. An ash-pit having an inwardly extending ledge, a grate rest disposed with the inner portion of the ledge extending 80 thereover, oppositely disposed aprons having their lower portions extending inwardly and downwardly and mountings for such aprons attached thereto and comprising upper and lower outwardly extending portions to properly support and space the aprons and embodying inwardly extending portions to overlap the grate rest.

4. In combination, an ash-pit, a grate rest disposed within the upper portion of 90 the ash pit, oppositely disposed aprons comprising lower portions inclining inwardly and downwardly and upper portions embodying vertical and lateral parts, the vertical parts of the apron extending along 95 the outer edges of the grate rest and the lateral parts extending outwardly and engaging the side walls of the ash-pit, and mountings for the aprons, each comprising an inclined portion, a vertical portion, upper and lower outwardly extending portions and an inner extension to overlap the grate rest.

In testimony whereof I affix my signature.
HENRY I. ROGERS. [L. S.]
